UNITED STATES PATENT OFFICE.

MORTIMER C. ROSENFIELD, OF CLEVELAND, OHIO.

FAUCET-SUPPORTING MEANS.

1,339,578.

Specification of Letters Patent. Patented May 11, 1920.

Application filed June 16, 1916. Serial No. 103,933.

To all whom it may concern:

Be it known that I, MORTIMER C. ROSENFIELD, a citizen of the United States, residing at Cleveland, in the county of Cuyahoga and 5 State of Ohio, have invented a certain new and useful Improvement in Faucet-Supporting Means, of which the following is a full, clear, and exact description, reference being had to the accompanying drawings. 10 This invention relates to improved means for supporting faucets within barrels or other containers during storage and shipment, and wherewith the faucets are intended for subsequent use; and the invention 15 has for its object to provide means whereby a faucet may be supported within a barrel or the like against liability of dislodgment, and into which the faucet may be readily placed and from which it may as 20 conveniently be removed.

In order to support the faucet far enough within the container to meet all practical requirements, it is necessary for the supporting means to extend some distance into the 25 container. This gives rise to a further object of my invention, and that is to provide the supporting means with openings located substantially flush with the inner surface of the container and through which the 30 container may be completely drained.

In the accompanying drawing I have shown an embodiment of my invention wherein the foregoing objects are attained, and while I will proceed to describe the 35 same in detail, it may be taken merely as illustrative, the scope of the invention being coextensive with the terms of the annexed claims.

In the drawing, Figure 1 is a fragmentary 40 sectional side elevation of a barrel equipped with the faucet supporting means of my invention and showing the same supporting a faucet within the barrel; Fig. 2 is a similar view of the barrel, inverted as for the purpose of draining; Fig. 3 is a perspective 45 view of the faucet supporting means detached from the barrel; Fig. 4 is a view of the supporting means from the inside, showing a faucet being inserted therethrough; Fig. 5 is a view of the same parts from the 50 outside and showing a faucet within the supporting means; and Fig. 6 is a sectional side elevation of the barrel with the faucet removed from the supporting means and applied to the bung, as in readiness for use.

I have shown my supporting means as

applied to the head 1 of a metal barrel 2, although it will be understood that the same may be located on the side of the barrel, if for any reason such an arrangement were 60 preferred, and that it may be associated with other sorts of containers.

The supporting means, which is represented generally at 5 in the drawing, may be formed of cast metal, drawn from sheet 65 metal, or produced by any other suitable method. In any event, it preferably comprises a wall 6, from the outer end of which a flange 7 extends laterally at substantially right angles, and from diametrically opposite sides of the inner end of which segmental flanges 8 extend inward. Between adjacent ends of the opposed flanges 8, the wall 6 is provided with notches or drain 70 openings 9 which extend from the inner 75 end of the wall 6 to within a distance of the inner surface of the flange 7 corresponding, substantially, to the thickness of the material of the barrel or container. Through these notches the container may be 80 completely exhausted of its liquid contents. The supporting means may be secured to the barrel by any suitable medium as, for instance, by welding. It may be explained, at this time, that in the case of metal barrels, 85 the supporting means may be formed as an integral part of the barrel. That is to say, the material of the barrel may be punched and formed to constitute the supporting means, and since such an alternative form is 90 so obvious, specific illustration thereof is deemed unnecessary.

The faucet that is intended for use in connection with my supporting means is composed, generally, of a tubular body 15, having one of its ends threaded at 16, and its opposite end turned laterally at a slight angle from its longitudinal axis and provided with a valve member having an operating handle 17, the spout 18 of the faucet extending laterally from the last mentioned end of the body portion in the direction opposite to that toward which the end is inclined. An enlargement 19, preferably shaped to constitute a wrench receiving portion, separates the threaded end 16 from the central body portion, and such enlargement is of a diameter slightly less than the internal diameter of the wall 6 of the supporting member, yet greater than the distance between 100 the inner edges of the opposed segmental flanges 8.

The faucet may be inserted through the supporting member in the manner illustrated in Fig. 4, the spaces between the ends of the segmental flanges 8 permitting the 5 spout 18 and the operating handle 17 to clear. When these parts are passed through the supporting means, the faucet may be dropped until its enlargement 19 bears upon the flanges 18 where it will be securely suspended by these engaging portions against any possible liability of dislodgment.

Other devices have been made for practically the same purpose as that for which my device has been produced, but none, so 15 far as I am aware, is proof against the faucet becoming detached from the supporting means and "lost" within the barrel, through the tumbling and jarring of the barrel in transportation. The difficulties experienced 20 through the dislodgment of the faucet can well be appreciated and emphasize the advantage of having the faucet supported absolutely against dislodgment in the manner provided by my invention.

25 The interior of the supporting member is threaded for the reception of a plug 20, having a wrench receiving portion 21, and the inner end of the plug is provided with a recess 22 for the accommodation of the threaded end 16 of the faucet, when the faucet is 30 in the supporting means and the plug in place. The barrel is equipped with a bung that may be provided with an internally threaded bushing 25 for the reception of the 35 threaded end 16 of the faucet, when it is desired to place the barrel in condition for use. In such condition, the opening occupied by the faucet supporting means is, of

course, closed by the plug 21. During shipment or storage, when the faucet is removed 40 from the bung, the bung may be closed by a plug 26.

Having thus described my invention, what I claim is:—

1. Means for supporting a faucet of the 45 type having an enlargement immediately inward of its threaded end, said means comprising an internally threaded tubular member having opposed segmental flanges extending inwardly from its inner end and 50 against which the enlargement of the faucet is arranged to bear when the faucet is inserted front end foremost through the member, the member having drain notches between said flanges, and a threaded plug for 55 closing the outer end of the member, the plug having a non-threaded recess for the accommodation of the threaded end of the faucet.

2. Means for supporting a faucet of the 60 type having an enlargement immediately inward of its threaded end, said means comprising a tubular member having opposed segmental flanges extending inwardly from its inner end and 65 against which the enlargement of the faucet is arranged to bear when the faucet is inserted front end foremost through the member, the wall of the member being provided with drain notches between adjacent ends of the opposed flanges, 70 and means for closing the outer end of the tubular member.

In testimony whereof I hereunto affix my signature.

MORTIMER C. ROSENFIELD.
